Primary Examiner — Lauren D McVey*Assistant Examiner* — Sarah L Smith(74) *Attorney, Agent, or Firm* — Knobbe, Martens, Olson & Bear, LLP(57) **CLAIM**

The ornamental design for a scooter, as shown and described.

DESCRIPTION

FIG. 1 is a front perspective view of a scooter of our design; FIG. 2 is a rear perspective view thereof; FIG. 3 is a front view thereof; FIG. 4 is a rear view thereof; FIG. 5 is a right side view thereof; FIG. 6 is a left side view thereof; FIG. 7 is a top view thereof; and, FIG. 8 is a bottom view thereof.

The broken lines depict portions of the scooter that form no part of the claimed design.
